UNITED STATES PATENT OFFICE.

HENRY C. WEEDEN, OF BOSTON, MASSACHUSETTS.

CHAIR-BED.

SPECIFICATION forming part of Letters Patent No. 352,723, dated November 16, 1886.

Application filed May 14, 1886. Serial No. 202,150. (No model.)

To all whom it may concern:

Be it known that I, HENRY C. WEEDEN, of Boston, in the county of Suffolk and State of Massachusetts, a citizen of the United States, have invented certain new and useful Improvements in Chair-Beds, of which the following is a specification.

My present invention relates to that class of devices in which an article of furniture—as, for example, a chair or lounge—is so constructed that it may be converted at pleasure into a bed; and its object is to improve the simplicity and effectiveness of such devices.

In the accompanying drawings, I have shown in perspective my improved structure arranged as a chair at Figure 1 and as a bed at Fig. 3. Fig. 2 represents a view in vertical section on the middle line of Fig. 1, and Fig. 4 a similar view on the middle line of Fig. 3. At Fig. 5 I have represented in perspective a view of a modification of Fig. 3, to be hereinafter described.

A represents the seat of the chair, and B B' its arms. C represents the back of the chair, and is provided with folding wings C' C². The arms B B', the back C, and the wings C' C² are all provided with suitable folding legs or supports for sustaining them when the chair is altered, as shown at Fig. 3, to form a bed, the seat A being supported by the chair-legs D, formed in the ordinary manner. Beneath the seat A may be provided a drawer or other convenient receptacle for receiving the bedclothes.

It will be understood that the parts A B B' C C² are to be suitably upholstered, to serve the conjoint purposes of a bed and chair.

When the back C is in position to form the back of a chair, I provide suitable hooks or fastenings, F F, adapted to hold it up, as shown in Fig. 1, but which may be disengaged when it is desired to lower it to form a bed, as shown in Fig. 3, it being understood that the angle of the back C to the bottom, when the device is used as a chair, should be such as will make the device convenient for such use.

It will be seen that in a device so constructed the entire length available for a bed is divided between the back C and the seat A of the structure. As this arrangement may involve in some cases an undesirable depth in the seat of the chair, a supplemental piece, G, (see Fig. 5,) is

provided with suitable folding leaves, G' G², may be hinged to the front edge of the seat A, so as to be folded down in front of the front legs thereof when the article is to be used as a chair, and to be folded up or flat, as shown in Fig. 5, to give additional area when the device is to be used as a bed. Suitable supports, as shown, are also to be provided for holding up the flap G and its connecting parts G' G². A counter-balance for the back C may be provided, if desired, and I have shown such a device in Fig. 5, consisting of cords H H, attached to the back C and passing through the seat A, and connected at their opposite ends to suitable springs or weights contained in boxes under the seat of the chair, one of which is represented at I in Fig. 5, the arm B being broken away to show it. It is, however, obvious that such a counter-balance may be dispensed with, if desired, or may be differently arranged and attached to the device.

I claim—

1. The improved chair-bed herein described, consisting of a seat, A, carried upon suitable supports, D, and provided with folding arms B B', and the folding back C, provided with folding wings C' C², and suitable fastening devices, F F, whereby the back C may be held up into position to form the back of a chair, and which may be disengaged to allow said back to be lowered to form part of a bed, all substantially as set forth.

2. In a convertible chair-bed, the combination, with the seat A, the arms B B', and the folding back C, provided with wings C' C², of the hinged extension G, provided with hinged leaves G' G², all substantially as shown.

3. In a convertible chair-bed, the combination, with the seat A and folding arms B B', of the folding back C, provided with suitable wings, C' C², said back being provided with a suitable counter-balance, substantially as herein set forth.

In testimony whereof I have hereunto subscribed my name this 12th day of May, A. D. 1886.

HENRY C. WEEDEN.

Witnesses:

E. B. TOMLINSON,
J. HENRY TAYLOR.
